United States Patent Office

Des. 185,525
Patented June 23, 1959

185,525

PARKING GARAGE

Adolph J. Adiletta, Stratford, Conn.

Application May 5, 1958, Serial No. 50,771

Term of patent 14 years

(Cl. D13—1)

FIG.1

FIG.3

Fig. 1 is a top plan view of a parking garage showing my new design;

Fig. 2 is a front elevational view thereof; and

Fig. 3 is a rear view thereof.

I claim:

The ornamental design for a parking garage, as shown.
